United States Patent Office.

FRANCIS A. PRATT, OF HARTFORD, CONNECTICUT, ASSIGNOR TO PRATT, WHITNEY AND COMPANY, OF SAME PLACE.

Design No. 3,611, dated August 10, 1869.

DESIGN FOR AN UPRIGHT DRILL.

The Schedule referred to in these Letters Patent and making part of the same.

To all whom it may concern:

Be it known that I, FRANCIS A. PRATT, of the city and county of Hartford, and State of Connecticut, have invented or discovered certain new and useful Improvements in Design for Upright Metal-Drilling Machines; and to enable others skilled in the art to make and use the same, I will proceed to describe it, referring to the drawings, in which the same letters indicate like parts in each of the figures.

In the accompanying drawings—

Figure 1 is a side elevation.

Figure 2 is a top or plan view thereof.

a is a perpendicular hollow column; *b* is a drill-stock; *c* is a movable bed-plate; *d* is an elevating and depress-

ing-lever; *d'* is a foot-lever; *e* is minum adjustable connection; *f* are actuating-pulleys; *g* are angle-pulleys; *h* are driving cone-pulleys; the whole intended as a new and useful design for an upright drilling-machine.

What I claim, therefore, and desire to secure by Letters Patent, is—

The design for an upright drill, substantially as shown and described.

FRANCIS A. PRATT. [L. S.]
